CASING HEAD

Harry P. Wickersham, Huntington Park, Calif.,
assignor to Baash-Ross Tool Company, Los
Angeles, Calif., a corporation of California

Application August 15, 1933, Serial No. 685,243

18 Claims. (Cl. 166—14)

This invention relates to a device for use on the upper end of a well and relates more particularly to a well casing head. It is a general object of the present invention to provide a simple, 5 compact and effective casing head.

In casing deep wells, for example, oil wells and gas wells, it is usually desirable to suspend or support the strings of casing from their upper ends so that they are maintained under a suitable slight tension, but it is not desirable to subject the strings of casing to excessive tensile strains. The usual casing heads are such that it is necessary to stretch the string of landed and set casing a considerable amount and thus 10 subject it to severe tensile strains in order to arrange the packing and casing supporting parts in position on the head. Further, the usual casing heads are large and bulky and expensive of manufacture.

20 An object of the present invention is to provide a casing head that does not necessitate the excessive stretching or straining of the casing when suspending it and inserting packing about it at the head.

25 Another object of the invention is to provide a casing head including a novel casing supporting assembly that may be easily and quickly arranged in the body of the head to be in supporting engagement with the lower end of the collar or coupling on the upper end of the casing without excessive stretching or straining of the casing.

30 Another object of the invention is to provide a casing head including an assembly adapted to be lowered or passed into the body of the head to a position where it will automatically engage under the coupling on the upper end of the casing without the necessity of stretching the casing to raise 35 the coupling out of the body.

It is another object of the invention to provide 40 a casing head of the character mentioned including an assembly adapted to be positioned in the body of the head to engage under the coupling on the upper end of the casing and a means for positively locking the casing supporting assembly in position.

45 It is another object of the invention to provide a casing head of the character mentioned that is operable to dependably and effectively pack and seal about the inner casing which it supports.

50 It is a further object of the invention to provide a casing head that is very small and compact and that is simple and inexpensive of manufacture.

55 Other objects and features of the invention

will be better and fully understood from the following typical form and application of the invention, throughout which description reference is made to the accompanying drawing, in which:

Fig. 1 is a vertical detailed sectional view of 5 the casing head provided by the present invention showing it in position on the upper end of an outer casing and in supporting and packing engagement with an inner casing. Fig. 2 is a transverse detailed sectional view taken as 10 indicated by line 2—2 on Fig. 1. Fig. 3 is a top- or plan view of one of the segmental supporting members. Fig. 4 is an elevation of the inner side of one of the segmental members, and Fig. 5 is an enlarged fragmentary vertical detailed sec- 15 tional view illustrating the casing supporting assembly after it has been positioned in the body of the head and before it has contracted on to the inner casing.

The casing head provided by the invention in- 20 cludes generally, a body 10 adapted to be mounted on the upper end of an outer casing C', an assembly 11 adapted to be inserted in the body 10 to support or suspend an inner string of casing C, a lock ring 12 for holding the assembly 11 in 25 casing supporting position, and means 13 for packing about the inner casing C.

The body 10 is a tubular structure or member 30 to be applied to the upper end of the outer casing C'. In the preferred construction, the body 10 is a simple integral member adapted to be connected with the outer casing C' by welding or screw threads. In the particular application of the invention illustrated in the drawing, the lower end portion 14 of the body 10 is externally 35 threaded to be screw threaded into the upper end of the outer casing C'. The opening 15 in the tubular body 10 is vertical and is concentric with the longitudinal axis of the outer casing C'. Fluid conduits 16 are threaded in openings 17 in the 40 wall of the body 10 to be in communication with the body opening and the interior of the outer casing C'. The upper end portion 18 of the body opening is of enlarged diameter so that an annular upwardly facing shoulder 19 is provided on 45 the interior of the body. An outwardly projecting annular flange 20 is provided on the exterior of the body 10 and is spaced below the upper end of the body.

The assembly 11 for holding or suspending the 50 string of inner casing C is adapted to be dropped or lowered into the body 10 to seat on the shoulder 19 and is operable to engage under the collar or coupling A on the upper end of the inner cas- 55 ing C, when the string of casing C is stretched

slightly to raise the collar. The upper length or section of the inner casing C is proportioned so that the lower end of the collar A is spaced between the shoulder 17 and the upper end of the body 10. The manner of providing for this proportioning of the upper section of casing C and the location of the coupling A will be subsequently described. The assembly 11 comprises a plurality of segmental members 21. The several members 21 are preferably alike in size and shape. The assembly of the segmental members 21 is annular or tubular and is frustro-conical when seated on the shoulder 19 in supporting engagement with the lower end of the coupling A. The lower ends 22 of the segmental members 21 are flat and are horizontal when the members are in their final casing supporting positions so that they are adapted to effectively seat on the upwardly facing body shoulder 19. The upper ends 22 of the segmental members 21 are flat, and when the members are in their operative positions, their upper ends 22 are horizontal and are in effective cooperation with the lower end of the coupling A. The inner and outer sides of the segmental members 21 are curved and are inclined downwardly and outwardly when the assembly is in the casing supporting position. The opposite ends of the several members 21 are flat and radial as illustrated throughout the drawing.

In accordance with the invention, the segmental members 21 constituting the assembly 11 may be proportioned so that their radial ends bear one against the other when the assembly 35 is in the casing supporting position to hold the inner sides of the members out of engagement with the casing C. The particular members 21 illustrated are provided on their inner sides at or adjacent their upper ends with cylindrically 40 curved faces 23 and are proportioned so that the faces are adapted to bear inwardly against the casing C. This engagement of the faces 23 with the casing C of course limits the inward movement of the members 21 and properly positions 45 the members to effectively engage under the coupling A. Circumferentially extending and aligned grooves are provided in the outer sides of the segmental members 21 to form an annular groove 25 in the assembly. The wall of the groove 50 25 is cylindrically curved about a vertical axis and the lower end or wall of the groove forms an upwardly facing horizontal shoulder when the assembly 11 is contracted on the casing C. Grooves are provided in the outer sides of the 55 several members 21 and are in circumferential alignment to constitute a single annular external recess or groove 26, when the assembly 11 is in its contracted or operative position.

It is an important feature of the present invention that the members 21 of the assembly 11 are shaped and proportioned so that they may be passed downwardly into the body opening 18 around the coupling A to positions where they are supported on the shoulder 19. By tilting the segmental members 21 to swing their upper ends outwardly, their inner and outer sides become substantially vertical so that when the assembly is passed into the opening 18, its inner and outer sides are substantially concentric with the wall of the body opening. The segmental members 21 are proportioned so that they may be passed into the body opening 18 with suitable clearance when tilted as just described. It is to be understood that the members 21 may be passed into the opening one by one. It is preferred however, to handle

the several members 21 as a single assembly, as will be presently described. When the assembly 11 is seated on the shoulder 19 its upper end 22 is spaced some distance below the upper end of the body 10.

Means is provided to hold the members 21 assembled to facilitate the convenient handling of the assembly. A constraining member or spring member 28 is arranged in the groove 26. The member 28 is in the nature of a broken or split ring of spring wire, or the like, and normally yieldingly urges the several members 21 inwardly. When the assembly 11 is to be passed into the body opening 18 around the coupling A, the segmental members 21 are pivoted on the spring member 28 to positions where their inner and outer sides are substantially vertical and the member 28 is then sprung to allow the assembly 11 to be passed downwardly over the coupling A into the opening 18. When the assembly 11 is seated on the shoulder 19, the upper inner corners of the several segmental members 21 engage the exterior of the coupling A adjacent its lower end. The inner casing C may then be stretched or elongated by the suspension mechanism in the derrick to raise the collar or coupling A out of engagement with the members 21 whereupon the members 21 may tilt inwardly by gravity to have their upper inner faces on or adjacent the casing. When the member 28 is in the form of a spring it may automatically contract the assembly 11 on to the casing C below the coupling A. The tension may then be removed from the string of casing C so that the lower end of the coupling A moves downwardly into engagement with the upper end 22 of the assembly 11. It will be apparent how the assembly 11 effectively supports the inner casing C and limits the return of the casing C to its normal length so that a suitable slight tension or tautness is maintained on the casing.

The lock ring 12 is adapted to be positioned in the opening 18 of the body to hold or lock the assembly 11 in its contracted position where it engages under the coupling A. The lock ring 12 is proportioned to fit into the opening 18 around the coupling A and has a reduced lower portion 30 to extend into the groove 25 in the assembly 11. The reduced lower portion 30 of the lock ring 12 has a cylindrically curved inner side to cooperate with the wall of the groove 25, and a flat horizontal end to seat against the lower end of the groove. The upper end 31 of the lock ring 12 is preferably flat and is spaced below the upper end of the body 10 to form an abutment or support for a packing ring.

The packing means 13 is provided to seal between the collar or coupling A and the body 10. The means 13 includes a ring 32 of suitable packing material arranged on the upper end 31 of the ring 12. The packing ring 32 may be substantially square or rectangular in cross section. The cylindrically curved external and internal faces of the packing ring 32 are operable to effectively seal with the wall of the opening 18 and with the collar or coupling A. Means is provided to compress the packing ring 32 and to lock or hold the various parts in the body opening. A compression sleeve 33 is arranged at the upper end of the body 10 and is provided with a downwardly projecting flange 34 to engage or clamp against the upper side of the packing ring 32. The sleeve 33 surrounds the upper end of the body 10 and is provided in its lower side with an annular recess 35 to receive the upper portion of the body. Studs

or bolts 37 extend through spaced vertical openings in the flange 20 and sleeve 33. Nuts 38 are threaded on the bolts 37 to clamp the sleeve 33 downwardly so that its flange 34 compresses the 5 packing ring 32 against the lock ring 12. It will be apparent how tightening of the nuts 38 effectively compresses the packing ring 32 so that it tightly seals between the body 10 and coupling A.

It is believed that the operation of the casing head provided by the present invention will be readily understood from the foregoing detailed description. After the inner string of casing C has been landed and cemented in, it is engaged by a holding tool at or adjacent the coupling connecting its upper section with the adjacent section. The upper section of the casing C is then backed off or unthreaded from the string. Prior to disconnection of the upper section from the string C, measurements are taken so that the disconnected section may be cut or shortened to have the lower end of the coupling A in the desired position within the body opening 18 when the section is again connected with the string. The inner string of casing may then be engaged or suspended by the suspension mechanism in the well derrick and the holding tool removed from the well. The novel casing suspending assembly 11 of the present invention may then be passed into the body opening 18. To prepare the assembly 11 for arrangement in the body opening 18, its several segmental members 21 are tilted or pivoted on the member 28 to positions where their inner and outer curved sides are substantially vertical and the member 28 is sprung or stretched so that the assembly may be readily passed downwardly over the coupling A into the opening 18. When the assembly 11 is initially seated on the shoulder 19, it assumes the position illustrated in Fig. 5 of the drawing where the upper inner corners of the members 21 engage the periphery of the coupling A. The inner string of casing C is then stretched or elongated slightly to permit the assembly 11 to contact on to the casing C below the lower end of the coupling A. It is necessary to stretch or elongate the inner string of casing C only an amount sufficient to bring the lower end of the coupling A to a position at the upper end of the assembly 11 to allow the members 21 to pivot or contract inwardly. When the members 21 are contracted, their faces 23 engage against the casing C and their lower ends 22 evenly seat on the shoulder 19. The lower end of the coupling A bears downwardly against the upper ends 22 of the members 21. As the inner string of casing C is stretched slightly to permit the contraction of the assembly 11, it is evident that the assembly 11 maintains a suitable slight tautness in the casing.

The members 21 constituting the assembly 11 are sufficiently rigid and sturdy to dependably support the string of casing C on the body shoulder 19. After the assembly 11 has been arranged in its operative casing supporting position, the lock ring 12 and the packing ring 32 are arranged in the body 18. The lock ring 12 in fitting against the exterior of the assembly 11 positively prevents the disengagement of the assembly from the lower end of the coupling A. The compression sleeve 33 may be readily arranged in position and clamped downwardly against the packing 32 by means of the bolts 37 and nuts 38. The present invention provides a casing head that dependably and effectively supports a string of inner casing and that provides an effective fluid tight seal around the upper end of the casing. It is to be particu-

larly noted that the casing supporting assembly 11 and the packing 32 may be arranged in operative positions in the body of the head without subjecting the casing C to heavy or excessive tensile strains. The casing head is compact and occupies a minimum amount of space at the upper end of the outer casing C.

Having described only a typical form and application of my invention, I do not wish to be limited or restricted to the typical form and application herein set forth, but wish to reserve to myself any modifications or variations that may appear to those skilled in the art or fall within the scope of the following claims:

Having described my invention, I claim:

1. A casing head for carrying a tubing having a projection including, a tubular body receiving the tubing and projection with clearance and having an internal shoulder, and an assembly adapted to be passed into the body when the projection is in the body to rest on said shoulder and to engage said projection to support the tubing, the assembly including means for automatically contracting against the tubing under the projection to assume a tubing supporting position.

2. A casing head for carrying a tubing having a projection including, a tubular body having an internal shoulder, and a segmental member adapted to be passed into the body to rest on said shoulder and to be tilted to engage under said projection to support the tubing.

3. A casing head for carrying a tubing having a projection including, a body having an opening for receiving the tubing and projection with clearance, an upwardly facing shoulder in the body, and a member shaped and proportioned to be passed into the opening when the projection is in the opening to rest on said shoulder and adapted to be tilted into a position in engagement with the projection to support the tubing.

4. A casing head for carrying a tubing having a projection including, a body having an opening for receiving the tubing and projection with clearance, an upwardly facing shoulder in the body, an assembly adapted to be passed into the opening when the projection is in the opening to rest on the shoulder where it may engage the lower end of the projection to support the tubing, and means for locking the assembly in engagement with the lower end of the projection, said means including a ring adapted to be arranged in the opening to encircle the assembly.

5. A casing head for carrying a tubing having a projection including, a body having an opening for receiving the tubing and projection with clearance, an upwardly facing shoulder in the body, a contractable assembly adapted to be passed into the opening around the projection to rest on said shoulder with its parts in substantially vertical positions, and means for contracting the upper end of the assembly on the tubing to cooperate with the lower end of the projection while the lower end of the assembly remains in contact with the shoulder.

6. A casing head for carrying a tubing having a projecting including, a body having an opening for receiving the tubing and projection with clearance, an upwardly facing shoulder in the body, and means for supporting the tubing on the shoulder said means including a plurality of members adapted to be passed into the opening when the projection is therein to rest on said shoulder, and to be tilted inwardly against the tubing to cooperate with the projection.

7. A casing head for carrying a tubing having a projection including, a body having an opening for receiving the tubing and projection with clearance, an upwardly facing shoulder in the body, and means for supporting the tubing on the shoulder said means including a plurality of members adapted to be passed into the opening when the projection is therein to rest on said shoulder, and means for tilting the members inwardly against the tubing to come into supporting cooperation with the lower end of the projection. 5
8. A casing head for carrying a tubing having a projection including, a body having an opening for receiving the tubing and projection with clearance, an upwardly facing shoulder in the body, and means for supporting the tubing on the shoulder said means including a plurality of members adapted to be passed into the opening when the projection is therein to rest on said shoulder 10 15
9. A casing head for carrying a tubing having a projection including, a body having an opening for receiving the tubing and projection with clearance, an upwardly facing shoulder in the body, and means for supporting the tubing on the shoulder including an assembly adapted to be passed into the opening around the projection to rest on the shoulder and initially engage the outer side of the projection, the assembly being adapted to contract inwardly toward the tubing when the projection is raised to be engaged by the lower end of the projection, and a ring in the opening for holding the assembly in the contracted position. 20 25 30 35
10. A casing head for carrying a tubing having a projection including, a body having an opening for receiving the tubing and projection with clearance, an upwardly facing shoulder in the body, and means for supporting the tubing including a member adapted to be passed into the opening when the projection is in the opening to have its lower end rest on the shoulder, the upper end of the member being adapted to tilt inwardly to engage under the projection upon the projection being raised and then lowered, and means for holding the member in the tilted position. 40 45 50
11. A casing head for carrying a tubing having a projection including, a body having an opening for receiving the tubing and projection with clearance, an upwardly facing shoulder in the body, and means for supporting the tubing including an annular assembly of a plurality of members, the assembly being adapted to be inserted in the opening around the projection to have the lower ends of its members bear on the shoulder, means for tilting the members inwardly so that their upper portions bear against the shoulders and their upper ends are engageable by the lower end of the projection, and means for holding the members in the tilted positions. 55 60 65 70
12. A casing head for carrying a tubing having a projection including, a body having an opening for receiving the tubing and projection with clearance, an upwardly facing shoulder in the body, and means for supporting the tubing including an annular assembly of a plurality of arcuate members, and a ring holding the members in assembled relation, the assembly being adapted to be inserted in the opening around the projection to have the lower ends of its members bear on the shoulder, the members being adapted to have their upper ends tilt inwardly so that their 75
- upper ends are engageable by the lower end of the projection, and means for holding the members in the tilted positions. 80 85
13. A casing head for carrying a tubing having a projection including, a body having an opening for receiving the tubing and projection with clearance, an upwardly facing shoulder in the body and means for supporting the tubing including an annular assembly of a plurality of members, the assembly being adapted to be inserted in the opening around the projection to have the lower ends of its members bear on the shoulder, the members being formed to tilt so that their upper ends are engageable by the lower end of the projection, there being a groove in the exterior of the assembly, and means for holding the members in the tilted positions, the last mentioned means comprising a ring to surround the assembly and fit in said groove. 90 95 100
14. A casing head for carrying a tubing having a projection including, a body having an opening for receiving the tubing and projection with clearance, an upwardly facing shoulder in the body, and means for supporting the tubing including an annular assembly of a plurality of members, the assembly being adapted to be inserted in the opening around the projection to have the lower ends of its members bear on the shoulder, and a spring ring engaging around the assembly to tilt the members inwardly to engage under the projection. 105 110 115 120 125
15. A casing head for handling a tubing having a projection including a body adapted to be arranged on the upper end of a well casing, the body having a vertical opening adapted to receive the tubing and the projection with clearance, a shoulder on the wall of the opening, an assembly adapted to be passed into the opening when the projection is therein to rest on said shoulder, the assembly including means for automatically contracting to engage under the projection to support the tubing on the shoulder, and means for packing between the projection and body. 130 135 140 145 150
16. A casing head for handling a tubing having a projection including a body adapted to be arranged on the upper end of a well casing, the body having a vertical opening adapted to receive the tubing and the projection with clearance, a shoulder on the wall of the opening, an assembly adapted to be passed into the opening over the projection to rest on said shoulder, the upper end of the assembly being adapted to contract toward the tubing whereby the assembly is operable to engage under the projection to support the tubing on the shoulder, a ring in the opening for holding the assembly in the tubing supporting position, and means for packing between the projection and body. 155 160 165 170 175
17. A casing head for handling a tubing having a projection including a body adapted to be arranged on the upper end of a well casing, the body having a vertical opening adapted to receive the tubing and the projection with clearance, a shoulder on the wall of the opening, an assembly adapted to be passed into the opening over the projection to rest on said shoulder, the upper end of the assembly being adapted to contract toward the tubing whereby the assembly is operable to engage under the projection to support the tubing on the shoulder, a ring in the opening holding the assembly in the tubing supporting position, and packing carried by the ring for sealing around the projection. 180 185 190 195 200
18. A casing head for handling a tubing having a projection including a body adapted to be ar- 205 210 215 220 225

ranged on the upper end of a well casing, the body having a vertical opening adapted to receive the tubing and the projection with clearance, a shoulder on the wall of the opening, an assembly adapted to be passed into the opening over the projection to rest on said shoulder, the upper end of the assembly being adapted to contract toward the tubing whereby the assembly is operable to engage under the projection to support the tubing on the shoulder, a ring holding the assembly in the tubing supporting position, packing carried by the ring for sealing around the projection and a compression sleeve extending into the opening for compressing the packing. 5

HARRY P. WICKERSHAM
